Primary Examiner — Janice Patyk*Assistant Examiner* — Kendra L Hebel(74) *Attorney, Agent, or Firm* — Baker Botts L.L.P.(57) **CLAIM**

The ornamental design for a spoon as shown and described.

DESCRIPTION

FIG. 1 is a top perspective view of a spoon showing my new design.
FIG. 2 is a left side view of the spoon of FIG. 1.
FIG. 3 is a right side view of the spoon of FIG. 1.
FIG. 4 is a top plan view of the spoon of FIG. 1.
FIG. 5 is a bottom plan view of the spoon of FIG. 1.
FIG. 6 is a front view of the spoon of FIG. 1.
FIG. 7 is a back view of the spoon of FIG. 1; and,
FIG. 8 is a top plan view of the spoon of FIG. 1, shown in unassembled condition, the bottom plan view being a mirror image.

The broken lines shown across the claimed surfaces in FIG. 8 show unclaimed fold lines of the spoon only and form no part of the claimed design.

1 Claim, 8 Drawing Sheets(56)
